United States Patent Office

Des. 195,125

Patented Apr. 30, 1963

195,125

ELECTRIC CAN OPENER

Downer P. Dykes, Lawrence, Kans., assignor to John C. Hockery, ½ Rival Manufacturing Company, Kansas City, Mo., trustee

Filed Sept. 27, 1962, Ser. No. 71,883

Term of patent 14 years

(Cl. D22—2)

Fig. 1.

Fig. 2.

Fig. 3.

Fig. 4.

FIG. 1 is a front elevational view of an electric can opener embodying my new design;

FIG. 2 is a side elevational view of the same taken from the left-hand side of FIG. 1;

FIG. 3 is a rear perspective view of same; and

FIG. 4 is a top plan view of same.

I claim:

The ornamental design for an electric can opener, as shown.
